I. GROLLMAN

DISPLAY DEVICE

Filed June 4, 1923

Inventor
Israel Grollman
By Luther Johns, vfty.

UNITED STATES PATENT OFFICE.

ISRAEL GROLLMAN, OF CHICAGO, ILLINOIS.

DISPLAY DEVICE.

Application filed June 4, 1923. Serial No. 643,174.

To all whom it may concern:

Be it known that I, ISRAEL GROLLMAN, a citizen of the United States, residing at Chicago, Cook County, Illinois, have invented certain new and useful Improvements in Display Devices, of which the following is a specification.

The present improvements relate to means or devices for displaying objects, as for sale, for instance objects or articles carried by bottles, packages or cartons, or objects or articles not enclosed, for instance shaving brushes, tooth brushes, knives, etc., etc., and a large variety of other articles and objects ordinarily displayed in stores.

The principal objects of the present improvements are to provide a display device of the kind referred to which may be produced at a reasonably low cost, which is simple in construction, which may be readily adapted to accommodate a large variety of articles of the same kind or of different kinds in a single display device, or in different devices, which is neat and attractive in appearance, which may be distributed flat or in knock-down condition and may readily be assembled by the user, and which does not suffer destruction or injury when the articles displayed thereby are removed for sale, and which may therefore be repeatedly recharged and made to serve its purposes during a relatively long period of use. Other objects and advantages will appear hereinafter.

In the accompanying drawings, which form a part of this specification, Figure 1 is a face view showing in fragmentary form a sheet-like supporting member carrying a strip forming a plurality of receptacles for objects or articles to be displayed; Fig. 2 is a fragmentary view of the supporting member of Fig. 1 showing how certain clips and rest members are formed integral with the sheet; Fig. 3 is a fragmentary horizontal sectional view as on the line 3—3 of Fig. 1; and Fig. 4 is a fragmentary face view of the strip-like piece of thin and flexible material showing how it is scored or indented for ready bending into the loop-like receptacles shown in Fig. 3.

The supporting member 10 may be considered to be of cardboard or any suitable thin sheet-like material. It may well be of metal and in some instances metal plate would be preferred owing to its additional

strength. It may be considered to have in practice any desired dimensions, and in my practice is given such size as readily to accommodate a considerable number of tiers or rows one above the other of articles or objects being displayed.

From Figs. 1 and 2 it will be noted that there is a normally upper series of tongues, lips or clips 11, 12, 13, 14, 15 and 16, and a similar normally lower series 17, 18, 19, 20, 21 and 22, these two series being in lines substantially parallel with each other. They will ordinarily extend horizontally, but they may well extend in the vertical direction if so desired. Each of these clips is shown as being cut free along three of its edges from the body of the supporting member 10 and pressed outward slightly away from the general plane of the member 10. It will be noted also that upper and lower clips are substantially opposite each other and constitute co-operating pairs of such clips, the members of which are directed toward each other. Adjacent ones of the upper series and adjacent ones of the lower series are correspondingly spaced apart in the longitudinal direction of the line of clips. As thus formed the upper and lower series of clips form substantially a channel adapted to receive a strip-like piece of thin and flexible material and to hold the same in position on the supporting member 10.

Such a strip of thin flexible material is shown in Fig. 4. The dotted lines 26, 27, 28 and 29 thereon indicate scoring, indenting or creasing adapted to cause the strip to bend readily on straight-across lines at those respective places.

The same reference characters 26, 27, 28 and 29 are shown in Fig. 3 where the bending of the strip 25 occurs. From Fig. 3 it will also be noted that the bend 29 occurs at one end of the clip 22 as the parts are assembled, and that the bend 28 occurs at one end of the clip 21, and also that the bend 27 occurs at the other end of the clip 21 and that the bend 26 occurs at one end of the clip 20. From Figs. 1 and 2 it will be clear that the upper clips hold the upper edge of the strip-like piece 25 in a corresponding way. The clips are therefore sufficiently long, or at least their ends are so positioned as to hold the strip-like piece 25 in loop-like formation against substantial enlargement. In other words, this loop-like struc-

ture, well shown in Fig. 3, is a locked construction, and the clips simultaneously hold the strip 25 in loop-like formation and also firmly secure it upon the supporting member 10.

The size and shape of the loop-like structure will in all instances depend upon that of the particular object or article to be displayed. I have shown an ordinary form of round bottle so held, but it is merely a matter of scoring or other mechanical practice to form these loop-like receptacles with other sizes or shapes as may be desired.

I have shown a window or sight-opening 15 in the strip 25 to indicate that if desired the advertising matter on the label of the article may thus be made to appear. In some instances it will be preferable to omit the sight-opening and to label or print upon the strip such advertising matter in connection with the individual articles as may be desired.

In Figs. 1, 2 and 3 will be noted an integral rest or holding member 32 normally 25 at the lower part of each of the receptacles or loop-like structures, this rest member 32 being cut out of the main body of the member 10 after the manner of forming the clips mentioned, and is bent outward substantially at right angles. Its normal position to act as a stop or rest is well shown in Fig. 3. Even when the supporting member 10 is formed of cardboard this outwardly extending tongue 32 acts as a sufficiently 35 strong support for holding such objects as bottles, tooth-paste containers, etc., since the construction is such as to develop shearing strains close to where this stop 32 is integral with the main supporting member 10.

The strip 25 is very easily assembled with the supporting member or carrier 10 since the clips numbered 11 to 22 inclusive may readily be bent upward slightly to facilitate entry of the edge portions of the strip, or 45 the strip itself may be bowed slightly to spring it under the clips, the loops being formed and the strip being caught beneath the upper and lower clips progressively be-

ginning at one end and continuing until the other end of the strip is reached.

I contemplate as being included in this invention such changes and modifications from what is herein specifically illustrated and described as fall within the scope of the appended claims.

I claim:

1. In a display device of the character described, the combination of a sheet-like supporting member, a strip-like piece of thin and flexible material formed into a series 60 of outwardly projecting loop-like receptacles, said strip-like piece extending normally substantially horizontally, normally upper and lower clips integral with the supporting member for holding said strip upon said supporting member and in loop-like formation, and a tongue integral with said supporting member and extending outwardly therefrom near the normally lower part of each of said loop-like formations to form a 70 bottom rest for an object held by each of said loop-like formations.

2. In a display device of the character described, the combination of a sheet-like supporting member having an upper series and a lower series of holding clips, the upper series and the lower series being substantially parallel with each other, clips of the upper series being substantially opposite respective clips of the lower series, said clips being integral with said supporting member and substantially opposite ones thereof being directed substantially toward each other and also outwardly away from the plane of the supporting member, the adjacent clips of said series respectively being spaced apart, and a strip of sheet-like flexible material held by and between the oppositely disposed clips, said strip being formed with a series of loop-like receptacles for objects to be displayed, said loop-like receptacles extending outwardly away from the plane of said supporting members and being spaced apart at said supporting member by said clips.

ISRAEL GROLLMAN.
